US00D652483S

(12) **United States Design Patent**
Nies et al.

(10) **Patent No.:** US D652,483 S
(45) **Date of Patent:** ** Jan. 17, 2012

(54) **SPRINKLER BASE UNIT**

(75) Inventors: **Juergen Nies**, Winchester, VA (US); **Ha Van Duong**, Winchester, VA (US); **Richard King Boyle**, Winchester, VA (US); **Vicky Ann Michael**, Winchester, VA (US); **James Daniel Carter**, Gerrardstown, WV (US); **Sean Svendsen**, Columbus, OH (US); **Nate Durflinger**, Columbus, OH (US); **Todd Mendoza**, Dublin, OH (US); **Eric Fickas**, Powell, OH (US)

(73) Assignee: **Melnor, Inc.**, Winchester, VA (US)

(**) Term: **14 Years**

(21) Appl. No.: **29/389,316**

(22) Filed: **Apr. 8, 2011**

(51) LOC (9) Cl. **23-01**

(52) U.S. Cl. **D23/221**

(58) **Field of Classification Search** D23/214, D23/216, 221; 239/242, 273, 276

See application file for complete search history.

(57) **CLAIM**

The ornamental design for a sprinkler base unit, as shown and described.

DESCRIPTION

FIG. 1 is a left, back perspective view of a sprinkler base unit showing our new design;

FIG. 2 is a right side view thereof;

FIG. 3 is a left side view thereof;

FIG. 4 is a front end view thereof;

FIG. 5 is a back end view thereof;

FIG. 6 is a top plan view thereof; and,

FIG. 7 is a bottom plan view thereof.

The broken lines illustrate environmental structure and form no part of the claimed design.

1 Claim, 7 Drawing Sheets
